COMBINED HOLDER AND DISPENSER FOR MATCHES

Filed Aug. 26, 1926.

INVENTOR
MORRIS MILLS.

BY *J. H. Weston, Haugh & Co.*
ATT'YS.

UNITED STATES PATENT OFFICE.

MORRIS MILLS, OF TRURO, NOVA SCOTIA, CANADA.

COMBINED HOLDER AND DISPENSER FOR MATCHES.

Application filed August 26, 1926, Serial No. 131,766, and in Canada January 19, 1926.

This invention relates to improvements in combined holders and dispensers for matches, and the objects of the invention are to provide a simply constructed and durable device of this description that can be hung up in any convenient position, which is adapted to hold a box of matches and to permit the matches to be readily extracted therefrom one at a time.

10 A further object is to provide a match box and dispenser of this description that can be manufactured at very low cost and readily marketed.

With the foregoing and other objects in view, as hereinafter more fully referred to, the invention consists essentially of a casing adapted to hold matches and formed with a spring back and a curved base having a cut out portion and slot therein and means carried by the spring back adapted to engage with the body of the casing to hold the box securely in position.

25 Referring now to the drawings, in which like characters of reference indicate corresponding parts in each figure:

Figure 1 is an enlarged perspective view of my improved holder and dispenser, with dotted lines showing the movement of the locking or retaining member,

30 Figure 2 is a longitudinal section through the device.

Referring now more particularly to the drawings, 10 designates a casing adapted to hold a box of matches, one end of which has 35 been broken open.

As illustrated in the present example of my invention, this casing is formed of any suitable material, such as tin, and is curved at the bottom as indicated at 11. In the 40 curved portion is a central V-shaped cut out portion 12 and at right angles thereto on one side a slot 13 slightly enlarged at the inner end, as at 14, to accommodate the head of a match. The front 15 of the casing is continuous, while the sides 16 and 17 are cut

out as at 18, permitting the back 19 to spring for the insertion of a box of matches.

For retaining the back securely in position when the box is inserted, I provide a clamp 20, here shown as formed of wire, suitably bent and pivotally carried at 21 in the turned edges of the back 19, the hook 22 serving as means by which the device may be hung in a convenient position.

After a box of matches has been inserted in 55 the casing 10 and the latter hung up by the hook 22 formed on the clamping member, the matches will automatically, by gravity, fall down into the curved bottom 11, some across the opening 12 and others partially protruding therefrom, but both readily accessible to anyone who wants a match. When the matches in the curved bottom 11 arrange themselves crosswise therein, the slot 13 enables them to be readily withdrawn without 60 danger through friction.

As many changes could be made in the above construction and many apparently widely different embodiments of my invention, within the scope of the claim, constructed without departing from the spirit or scope thereof, it is intended that all matter contained in the present specification and accompanying drawings shall be interpreted in an illustrative and not in a limiting sense. 75

What I claim as my invention is:

A combined match holder and dispenser comprising a casing formed with a curved base having a central cut out portion therein and a slot on one side of the cut out portion and at right angles thereto, a continuous front and back for the casing and partially cut out sides adapted for the insertion of a box, and a clamping member pivotally mounted on the back, designed to engage 80 with the front to clamp the front and back together on said box.

45 In witness whereof I have hereunto set my hand.

MORRIS MILLS.
